Primary Examiner — Robin V Webster(74) *Attorney, Agent, or Firm* — Michael Best & Friedrich LLP(57) **CLAIM**

We claim the ornamental design for a shower, as shown and described.

DESCRIPTION

The FIGURE is a front view of a shower.

Any broken line showing of the environment is for illustrative purposes only and forms no part of the claimed design. The broken lines having unequal length segments represent the boundaries of the claimed design and form no part of the claimed design.
